FIG. 5

FIG. 1 is a side elevational view of a holder for belts or the like embodying my new design.

FIG. 2 is a similar view showing the holder as it appears when turned about its upright axis through an arc of 90 degrees relative to the position of the holder as shown in FIG. 1.

FIG. 3 is a top view of the holder.

FIG. 4 is a bottom view of the holder.

FIG. 5 is a perspective view of the holder.

The essential features of my design comprise the downwardly and outwardly bevelled peripheral contour of the central circular portion of the holder in combination with arms of uniform size and shape extending radially from said central portion a distance at least double the radial dimension of said central portion, said arms having flat upright opposed faces except for spheroidal segmental portions projecting from said faces of each arm, said pro-

jecting portions occupying positions uniformly away from said central portion a distance greater than the radial dimension of said central portion and substantially coextensive with the upright dimension of said arms.

I claim:

The ornamental design for a holder for belts or the like, as shown and described.
